UNITED STATES PATENT OFFICE

SWAN NELSON, OF CHICAGO, ILLINOIS

CORN POPPER

Application filed April 1, 1929. Serial No. 351,749.

My invention relates to corn popping machines, and more particularly to those which are on display in stores, windows or on stands and wagons and my main object is to produce a machine of this kind which operates with a minimum of parts.

A further object of the invention is to so design the machine that it occupies but a small portion of the space within the display case usually housing machines of this kind.

A still further object of the invention is to provide an automatic action for the agitation of the corn kernels which is closely associated with the oven in which the popping is done, confining the heat to the region of the oven.

Another object of the invention is to so design the agitating action and the oven that the latter may be heated with facility by electricity.

A significant object of the invention is to construct the novel machine with a simple and efficient kernel feed, which requires no manual attention for its action.

A final but nevertheless important object of the invention is to build the novel machine along lines of ready access and evident simplicity, in order that it may function efficiently for long periods.

With the above objects in view and any others that may suggest themselves from the specification and claims to follow, a better understanding of the invention may be had by reference to the accompanying drawings, in which—

Figure 1 is a vertical section of the display case and the machine within it, some parts being shown in elevation and others broken away;

Figs. 2, 3 and 4 are sections on the lines 2—2, 3—3, and 4—4 of Figure 1; and

Fig. 5 is a detail section taken on the line 5—5 of Figure 3.

Machines of the character mentioned are usually glass enclosed, the product piling up in a glass case, such as is shown at 10. For purposes of clearness, the machine as illustrated in Figure 1 occupies the greater portion of the case 10, but in reality the ma-

chine will be disposed in the upper part of the case, leaving the larger portion thereof for the accumulation of the popped corn and the disposal of accessories and possible other confections, such as peanuts, popcorn balls, etc.

The main portion of the machine consists of an elongated oven 11, having a flat top 11a and a trough-shaped bottom 11b. The cross section of the oven is generally semicircular so that its ends may receive at the top a shaft 12, carrying a sweep arm 13 which travels over the bottom of the oven back and forth as the shaft is rocked. The oven is preferably supported in the top of the case by a set of rods 10a. My intention is that a measured quantity of corn kernels be dropped into the oven, the charge then being agitated by the action of the sweep arm 13 until popped, at which time it is discharged. While the oven may be heated by any means for this purpose, I prefer for compactness and safety the use of an electrical heating element 14, suitably encased by an oven jacket 15.

The roof of the oven receives a vent pipe 16 which rises through the top of the case 10. At one side, the oven bottom has a separate portion 11c which is hinged at the top as indicated at 11d to swing outwardly from the oven as shown by dotted lines in Figure 3. This action opens the affected side of the oven, permitting the discharge of its contents into a scoop extension 17 of the portion 11c. The popped corn filling the scoop 17 in its departed position, indicated by the dotted lines in Figure 3, falls directly out of the scoop and down into the case. Unpopped kernels, however, being of smaller size and heavy gather enough momentum

when coursing down the scoop to leap across into the mouth 18a of a discharge funnel 18, which as indicated in Figure 1, tapers to extend downwardly with a waste pipe 19. Thus, the unpopped corn is automatically expelled.

The operation of the sweep arm 13 is necessarily rapid in order to protect the corn from burning, and is induced primarily by an electric motor 20 mounted on top of the case 10.

and having a suitable switch control 21. The drive from the motor is first taken through a chain 22 to a jack shaft 23 from which it is transferred through a chain 24 to a wheel 25 in one end of the oven jacket 15. This wheel imparts an oscillating motion to an adjoining wheel 26 through the agency of a pitman 27, so that each time the wheel 25 takes a revolution the wheel 26 oscillates in one and the 10 opposite direction. The wheel 26 being carried by the oven shaft 12, it is evident the sweep arm 13 receives a constant oscillating motion across the floor of the oven. The sweep arm is carried by radius rods 12a extending from the shaft, and is generally made of triangular section as indicated in Figure 3, so that on its sweep toward the discharge portion 11c it will present a front and push the oven contents ahead of it, while on the way 20 back it will pass under the contents so as not to crowd them in the remote portion of the oven.

The sweep arm 13 is made of full rectangular section as indicated at 13a in Figures 25 3 and 4 at the points where it is met by the radius rods 12a, that the latter may be screwed into the full portion of the sweep arm to firmly connect with the same.

The machine is timed to open the discharge 30 portion 11c of the oven periodically, the drive being taken from the jack shaft 23. Accordingly, the latter carries a bevel gear 28 at one end to make connection with a companion gear 29 carried by a vertical shaft 30. This 35 shaft descends to a position inside the corresponding end of the oven jacket 15, as more clearly shown in Figure 3, carrying a worm pinion 31 thereat. The worm pinion makes a meshing connection with the periphery of a worm gear 32 rotatably mounted in a bearing 33 and independently of the shaft 12 which is also carried by said bearing. The gear 32 carries a wing cam 34 which as the gear turns in a counter-clockwise direction strikes a 40 lateral bend 35a of an arm 35 extended inwardly from the oven discharge portion 11c over one end of the oven. This action guides the portion 11c outwardly, as indicated by dotted lines, for the proper period during 45 which the contents of the oven are to be discharged, after which—the swing cam 34 having cleared—a spring 36 on the end of the oven draws the discharge portion 11c shut. Thus, the latter is normally closed, and is not 50 affected by any running gear during the time of popping; and the action to open the portion is a simple one.

The corn kernels are usually stored in a glass container 37 whose bottom opens into a 55 hopper 38 at the top of the case 10. The hopper converges to open into a measuring shaft 39 below which is a hopper 40 which opens directly into the oven 11.

The discharge opening in the hopper 38 is 60 controlled by a stopper 41, which is hung on

the inner end of an arm 42 fulcrumed at 43 in the wall of the hopper and extending to become linked at 44 to a depending lever 45. When the lever 45 is given a downward pull the stopper 41 is made to rise, permitting the 70 kernel corn to sweep down into the shaft 39. The latter has a bottom lid 39a hinged to the shaft at 39b and automatically closed as will later be explained. Thus, the shaft 39 becomes filled and remains so until it is time to 75 discharge its contents into the lower hopper 40.

The control for the depending lever 45 is simply a round stud 46 on the inner face of the gear 32. The bottom of the lever 45 is 80 linked as indicated at 45a to one end of an arm 47, the opposite end thereof being pivoted at 48 to the corresponding end of the oven. As seen in Figure 4, when the gear 32 travels in a counter-clockwise direction 85 whereby to bring the stud 46 in a downward course, the arm 47 is so placed as to be crowded to a limited degree by the stud as it passes, this drawing downwardly upon the lever 45 and causing the stopper 41 to be lifted, as 90 previously explained. After the stud 46 has actuated this operation, the lever 45 will be caused to automatically rise to its normal position by the stopper 41, which is weighted to accomplish this.

Referring to Figure 4, it will be seen that the bottom lid 39a of the shaft 39 has a radial extension 49 from its hinge 39b, which according to Figure 1 has a lateral arm 50 ordinarily drawn in an upward direction by a spring 51 leading to the top of the case, this having the effect of normally keeping the lid 39a closed. The extension 49, however, receives a downwardly directed rod 52 which passes down into the oven jacket by way of a bearing 53 and terminates with a bend 54 which is parallel and in proximity to the gear 32. The said bend is also in the path of the gear stud 46, and when the latter travels as indicated in Figure 4, the effect is that the rod 52 is drawn downwardly against the tension of the spring 51 to open the lid 39a and discharge the contents in the shaft 39 into the hopper 40 for delivery into the oven.

It will be observed that the gear stud 46 first actuates the rod 52, causing the discharge just mentioned. Then, the stud actuates the lever 45 for the refilling of the shaft 39 as the lid 39a is drawn shut when the stud 46 clears the bend 54 of the rod 52. According to Figure 4, it is evident that the two operations just described occur in close succession, after which the gear 32 travels a comparatively long time before again reaching the parts affected. If a filling has been imparted to the oven, sufficient time for the popping operation must ensue before a new filling is imparted, so that the gear 32 is necessarily driven at a very slow rate.

The interim between the discharge action 130

of the lid 39a and the opening of the stopper 41 is of significance. As the shaft 39 empties, the inference would be that the stopper 41 being cleared from below by the falling kernels 5 would yield in an upward direction from the kernels surrounding it to let these escape down into the shaft 39 and thus feed an overdose of corn to the oven. This does not occur, however, since the kernels in the hopper 10 38 exert a crowding action upon the upper part of the stopper 41, which is incidentally conical, whereby to jam the surrounding kernels and cut off their passage. The action of the hopper 38 is thus at a standstill until 15 the lid 39a has swung shut and the lever 45 been pulled down to lift the stopper 41 to a sufficient degree to permit the passage of the kernels.

It will be seen that in the novel machine 20 the sweep arm 13 is driven by a positive and simple power connection, and that the elements dealing with the feed of the corn are also simple, readily accessible and of a rugged nature, rendering the construction of the 25 machine relatively inexpensive and the operation of the same efficient and not liable to attention for long periods.

I claim:—

1. A corn popper comprising a trough-like 30 oven of part-circular cross-section, a shaft in the top of the oven and adapted to receive a rocking movement, and a sweep arm carried by the shaft for motion across the floor of the trough, a door carried by the oven, 35 said sweep arm adapted to periodically discharge the contents of the oven through the door.

2. A corn popper comprising a trough-like oven of part-circular cross-section, a shaft in 40 the top of the oven and adapted to receive a rocking movement, and a sweep arm carried by the shaft for oscillatory motion across the floor of the trough, a door hingedly carried by the oven, said sweep arm adapted to periodically discharge the contents of the oven 45 through the door.

3. A corn popper comprising a trough-like oven of part-circular cross-section, a shaft in 50 the top of the oven and adapted to receive a rocking movement, and a sweep arm carried by the shaft for motion across the floor of the trough, said sweep arm presenting a front substantially perpendicular to said floor in one direction of its movement, and tapering 55 in the opposite direction to meet the floor of the trough.

4. A corn popper comprising an oven 60 formed with an outlet, a gate opening from the latter for the expulsion of popcorn and unpopped kernels, and means beyond the gate inducing the discharge of the popcorn in one direction and the unpopped kernels in another direction.

5. A corn popper comprising an oven 65 formed with an outlet, a gate opening from

the latter for the expulsion of popcorn and unpopped kernels, and a chute leading from the gate and scoop-shaped to induce momentum in the relatively heavy unpopped kernels for discharge as projectiles. 70

6. A corn popper comprising an oven formed with an outlet, a gate opening from the latter for the expulsion of popcorn and unpopped kernels, a chute leading from the gate and scoop-shaped to induce momentum 75 in the relatively heavy unpopped kernels for discharge as projectiles, and a receiver opposite the chute to catch said kernels.

7. A corn popper comprising an oven formed with an outlet, a gate opening from the latter for the expulsion of popcorn and unpopped kernels, a chute leading from the gate and scoop-shaped to induce momentum 80 in the relatively heavy unpopped kernels for discharge as projectiles, and a receiver opposite the chute to catch said kernels, said receiver being spaced from the end of the chute for clearance by the relatively light popcorn in rolling off and dropping from the chute. 85

8. A corn popper comprising an oven 90 formed with an outlet, a gate for the latter and normally closed, oscillatory means to agitate the oven charge to and from the outlet at a rapid rate, a slow-rate gearing, and a cam carried by the latter to induce the opening of the gate at predetermined intervals with the effect of the expulsion of the charge by the oscillatory means. 95

9. A corn popper comprising an oven 100 formed with an outlet, a gate for the latter and normally closed, oscillatory means to agitate the oven charge to and from the outlet at a rapid rate, a slow-rate gearing, an arm carried by the gate, and a cam in said gearing to crowd said arm and induce the 105 opening of the gate at predetermined intervals with the effect of the expulsion of the charge by the oscillatory means.

10. A corn popper comprising an oven having an inlet, a discharge gate for the oven, 110 a power element, a connection from the latter to operate the gate at predetermined intervals, a feed vessel opposite the inlet for the supply of the oven, a discharge valve for the vessel, a measure communicating with the vessel by way of the discharge valve and leading to the oven inlet, a valve between the measure and the latter, levers operating the respective valves, and a cam moved by the power element and effective upon the levers 115 in timed relation with the gate. 120

In testimony whereof I affix my signature.
SWAN NELSON.
